UNITED STATES PATENT OFFICE.

JOHN WISDOM GONCE, OF ANDERSON, TENNESSEE.

DENTIPHONE.

Application filed October 29, 1924. Serial No. 746,682.

The present invention relates to new and useful improvements in dentiphones, and it pertains more particularly to an improvement over the device shown in my United States Letters Patent No. 1,472,214, granted to me October 30, 1924.

It is one of the objects of the present invention to provide a device adapted for use with talking machines in order to reproduce the records used thereon in such a manner that deaf persons may enjoy the same.

It is a further object of the invention to construct a device of this character in such a manner that a maximum volume of sound may be had.

It is a further object of the invention to construct the device in such a manner that the stylus or needle may be positioned at various angles relative to the dentiphone.

With the above and other objects in view, reference is had to the accompanying drawings, in which—

Figure 1 is a view in elevation of one form of dentiphone constructed in accordance with the present invention;

Fig. 2 is a similar view thereof taken at right angles to Fig. 1;

Fig. 3 is a detail view of a modified form of the invention, in which the device comprises two sections detachably secured together;

Fig. 4 is a view of the two sections of the device in disassembled relation;

Fig. 5 is a detail sectional view showing the manner in which the two sections of the dentiphone are detachably secured together;

Fig. 6 is a detail sectional view of the head of the dentiphone showing the manner of mounting the stylus or needle therein;

Fig. 7 is a detail view partly in section showing the mouth end or head of the dentiphone;

Fig. 8 is a detail sectional view showing a slightly modified form of head and stylus holder.

Referring more particularly to the drawings, the reference numeral 10 designates the body portion of the dentiphone, and such body portion is provided with a stylus or needle end 11 and a mouth end 12. The stylus or needle end 11 is provided with a stylus-receiving head 13 having one or more angularly disposed recesses 14 therein for

the reception of a stylus. The portion intermediate this stylus head and the central portion 10 is relatively thin as designated by the reference numeral 15, and as more clearly shown in Fig. 2, that portion of the dentiphone between the body 10 and the mouth end 12 is relatively thin as designated by the reference numeral 16, and as shown in Figs. 1 and 2 these portions 15 and 16 are relatively thin in planes at right angles to each other. The mouth end 12 is provided with a removable cap, or the like, 17, which removable cap is formed of fiber, paper, or similar material, and is used for sanitary reasons.

In using this form of the invention, a stylus is placed in one of the several openings 14, the opening employed being determined by the position of the person using the device relative to the talking machine. After the stylus has been positioned, it is engaged with the record, it being understood that the opposite end of the device is placed between the teeth of the operator. If, now, the talking machine be started, the travel of the stylus through the sound groove of the record will cause the vibration set up by the record to be transmitted through the body of the dentiphone and through the teeth of the user, and will thus transmit all of the tones and sounds to the user in a clearly understandable manner.

In that form of the invention shown in Figs. 3 to 5 inclusive, the device comprises two members 20 and 21. Each of these members has a main body portion which is substantially rectangular in cross sectional form, and such members have relatively thin flattened portions 22 and 23, respectively. The member 20 is provided with a stylus or needle head 24, and the member 21 is provided with a mouth end 25 having a protecting cap 26, as in the heretofore described form of the invention. As shown in the drawings, the member 21 is bifurcated as at 27, and the member 20 has a tenon 28 adapted to be received within the furcations of the bifurcated member 21. A bolt passes through the furcations of the bifurcated member 21 and through the tenon 28 of the member 20, the bolt being designated by the reference numeral 29. This bolt carries a wing nut 30, or the like, by means of which the furcations may be placed under

tension to frictionally engage the tenon 28 to permit of adjustment of the members 20 and 21 relative to each other.

For the purpose of convenience in carrying or shipping, the two sections 20 and 21 may be separate from each other, and owing to the opposite directions in which they are curved, they nest in a compact space as shown in Fig. 4.

10 It will be noted that the position in which the tenon is placed on the end of the member 20 and the position in which the furcation is placed on the member 21, throw the relatively thin portions 22 and 23 at right angles to each other so that they occupy positions similar to that in the previously described form of the invention, that is, at right angles to each other.

In Fig. 8 is shown a slightly modified form of stylus head 10, and in this figure the reference numeral 40 designates a plurality of stylus- or needle-receiving openings 41, 42, 43 and 44. This construction permits of the positioning of a stylus at various angles to the dentiphone in such a manner that the stylus may be used upon either side of the head, and either to the right or left of the central point of the record or table upon which it is mounted.

25 30 From the foregoing it is apparent that the present invention provides a device which will permit persons deaf or non-deaf

to enjoy the pleasure afforded by the use of phonographs and the like.

It is also apparent from the above that all of the objects of the present invention have been accomplished, and, further, it should be understood that numerous modifications of structure might readily be resorted to without in the least departing from the scope of the claims.

What is claimed is:—

1. A device of the character described comprising a plurality of resilient members, means for adjustably securing said resilient members together, a stylus head carried by one of said members, and a mouth piece carried by the other of said members. 45

2. A device of the character described comprising a plurality of resilient members adjustably secured together, said members being disposed in planes at right angles to each other. 50

3. A device of the character described comprising a plurality of resilient members, means for pivotally securing said members together, a stylus-carrying head formed on one of said members and a mouth piece carried by the other of said members, said mouth piece being positioned in a plane at right angles to that of the stylus-carrying head. 55 60

JOHN WISDOM GONCE.
